UNITED STATES PATENT OFFICE.

RICHARD GHISELIN, OF WEBSTER GROVES, MISSOURI.

BLIND-HINGE.

SPECIFICATION forming part of Letters Patent No. 326,729, dated September 22, 1885.

Application filed February 26, 1884. (Model.)

To all whom it may concern:

Be it known that I, RICHARD GHISELIN, of Webster Groves, St. Louis county, Missouri, have made a new and useful Improvement 5 in Blind-Hinges, of which the following is a full, clear, and exact description, reference being had to the annexed drawings, making part of this specification, in which—

Figure 1 is a view in perspective of the 10 improved hinge, and Fig. 2 a top view, the blind and window frame being in section.

The same letters of reference denote the same parts.

The present invention is an improvement 15 more especially in self-locking blind-hinges. The leaves of such hinges are apt to break at a point between the knuckle and the outer broader end of the leaf. To obviate this difficulty I provide a shoulder, against which 20 the side of the blind can abut, and to furnish additional means for connecting the hinge with the blind and window frame is the aim of this improvement, which consists in providing the narrow inner end of the leaf with 25 a rib which projects at right angles from such narrow inner end and extends from the region of the knuckle toward the outer end of the leaf and to meet (when the hinge is attached in position) the side of the blind in 30 the case of one of the leaves of the hinge, and the side of the window-frame in case of the other of the hinge-leaves. The rib is also constructed so that a screw, nail, or other equivalent fastening may pass through the 35 rib into the blind or window frame, as the case may be, and thereby fasten the hinge at those points to the blind and window frame, respectively, in addition to the usual fastenings hitherto used in attaching the 40 hinge.

A, Fig. 1, represents a hinge of the class under consideration, and one exhibiting the improvement.

B B' represent the leaves of the hinge.

45 C represents the knuckle, and D D represent the outer ends of the leaves, respectively.

Aside from the improvement the hinge is of the usual description.

50 E represents the rib with which the leaf of the hinge is provided. It projects from the

narrow part F of the leaf, and it extends from the region of the knuckle toward the outer end of the leaf to meet the blind H or window-frame G, as the case may be, and as 55 shown in Fig. 2. When it is thus extended it, as is seen, serves as a shoulder to support the blind sidewise in case of one of the leaves and to support the other leaf against the window-frame. The hinge is attached in the 60 usual manner, by means of fastenings passing through the ordinary perforations d d, and the rib has an eye, e, through which an additional fastening (not shown, but indicated in dotted lines) can pass, and thence into the blind or 65 window frame.

As shown in the drawings, the leaves B B' can be interchangeably applied to the blind or window frame; but in some cases, and to suit a special construction of window-frame, 70 the rib upon the leaf which is attached to the window-frame may be modified.

It will be observed that by placing the perpendicular face of the edge a¹ of the inclined braces E E at right angles to the face of the 75 plate D, the horizontal faces a² of the braces E E will also be at right angles to the face of the sides of the plate D, thus forming a very strong brace.

I am aware that a hinge has been made 80 having two flat outer ends which are adapted to be secured to the window-frame or blind-frame at or through their sides, and I therefore disclaim such construction; but as I design to secure my hinge to the blind or window frame at and through the rib E, and as I believe this to be new and novel, as it is of great importance, I do claim and desire to secure by Letters Patent—

As an improved hinge for shutters, the 90 leaves B and B', provided with the outer perforated ends, D D, and also provided with the inclined ribs E E, having perforations e, the horizontal faces a² of which extend at right angles to the portions D D and form braces 95 and re-enforcements therefor, in combination with the pintle C, substantially as set forth.

R. GHISELIN.
